US00D812122S

(12) **United States Design Patent** (10) **Patent No.:** **US D812,122 S**
(45) **Date of Patent:** **** Mar. 6, 2018**

(54) **ROBOT HAND**

(71) Applicant: **Softbank Robotics Europe**, Paris (FR)

(72) Inventors: **Vincent Clerc**, Clamart (FR); **Robert Hong**, Paris (FR)

(**) Term: **15 Years**

(21) Appl. No.: **29/572,485**

(22) Filed: **Jul. 28, 2016**

(30) **Foreign Application Priority Data**

Jan. 29, 2016 (EM) 002963637-0003

(51) **LOC (11) Cl.** **15-99**

(52) **U.S. Cl.**

USPC **D15/199**

(58) **Field of Classification Search**

USPC D15/126, 138, 199; D21/345, 350, 360, D21/361, 362, 383, 384, 398, 399, 414, D21/415, 418, 428, 455, 503, 504, 528, D21/529, 558, 578, 579, 594, 612, 621, D21/627, 658; D24/138, 155, 185, 198, D24/205, 208, 211, 231, 232; D29/124, D29/129; D34/35; D99/1, 17, 30, 34, D99/37, 38, 99

(57) **CLAIM**

The ornamental design for a robot hand, as shown and described.

DESCRIPTION

FIG. 1 is a top front view;

FIG. 2 is a top back view;

FIG. 3 is a back bottom view;

FIG. 4 is a front bottom view;

FIG. 5 is a front view;

FIG. 6 is a back view; and,

FIG. 7 is a side view.

The broken lines show portions of a robot hand that form no part of the claimed design.

1 Claim, 7 Drawing Sheets
